CLAIM

The ornamental design for a photocatalytic lamp module for an air purifier, as shown and described.

DESCRIPTION

FIG. 1 is a perspective view of the photocatalytic lamp module for an air purifier;

FIG. 2 is a left side elevation view thereof;

FIG. 3 is a right side elevation view thereof;

FIG. 4 is a top plan view thereof;

FIG. 5 is a front elevation view thereof;

FIG. 6 is a rear elevation view thereof; and,

FIG. 7 is a bottom plan view thereof.

The broken line showing is included for the purpose of illustration only and forms no part of the claimed design.
